RESTARTING CONTROLLER FOR SHUTTLE
CHANGING LOOMSLewis S. Vose, Needham, Mass., assignor to
Crompton & Knowles Loom Works, Worcester,
Mass., a corporation of Massachusetts

Application May 10, 1932. Serial No. 610,410

11 Claims. (Cl. 139—227)

My invention applies to weft replenishing looms particularly to the shuttle changing types that effect replenishment during a temporary suspension of the weaving instrumentalities, and 5 is equally applicable to either the single or the multicolor type. Its purpose is to provide means that will prevent the starting of the loom automatically after a replenishing cycle unless a shuttle has been properly ejected from the lay. 10 Devices are common in looms of this type to prevent the insertion of a fresh shuttle in the event that one is not ejected but I believe that means to render the starting mechanism inoperative under such conditions is entirely new. It will 15 prevent possible injury to an operative due to inadvertently tripping the changing mechanism into action while making adjustments and being caught when the loom starts.

With these and other objects in view which 20 will appear as the description proceeds, my invention resides in the combination and arrangement of parts hereinafter described and set forth in the claims.

In the accompanying drawings, wherein a 25 convenient embodiment of my invention is set forth,

Fig. 1 is a side elevation of a loom having my invention applied thereto, portions of the lay and shuttle box being in section,

30 Fig. 2 is a front elevation of a portion of Fig. 1 viewed from the left hand side of the latter,

Fig. 3 is an operating view of portions of the structure shown in Fig. 1, and

35 Figs. 4 and 5 are operating views showing the parts in different positions as the shuttle passes into the receiver box.

Referring to the drawings, I have shown a loom frame 1, a replenishing magazine 2, and a lay 3 pivoted at 4 and having swords 5. A change shaft 6 extends across the loom and performs the functions common to a similar shaft described in my co-pending application United States Serial No. 603,051 during the replenishment period when the loom is at rest.

40 45 A filling feeler mechanism such as disclosed in my co-pending application United States Serial No. 593,814 stops the loom upon deficiency of filling, and starts rotation of shaft 6, one complete rotation of which effects weft replenishment 50 and starts the loom running again.

When the feeler indicates a change the loom 55 is stopped and a rotation of the change shaft 6 is initiated by well-known means as set forth in United States Patent 1,100,866 granted June 23, 1919 to S. S. Jackson, during which the spent

shuttle is ejected from and a fresh one inserted on the lay.

The box front 7 is raised by lifter 8 fulcrumed at 9 in stand 10 mounted on the back of the lay, through action of cam 11 on change shaft 6 60 actuating lever 12 connected to lifter 8 by connector 13 and fulcrumed at 14. When the front 7 is elevated to an extent sufficient to permit ejection of the depleted shuttle, the lifter engages screw 15 in ejector lever 16, causing the latter to 65 rock on shaft 17 mounted on lay carried stand 10, and move ejector 18 forward beneath binder 19 to push against the lower back wall of the 70 depleted shuttle and eject it forwardly off the lay.

A cam 21 on the change shaft actuates a conveyor lever 22 through roll 23 mounted on said lever at 24. Lever 22 is pivoted at 25 on the loom frame and a spring 26 fastened to the frame acts on the lever to keep the roll in contact with the 75 cam and draw said lever yielding toward the lay. Lever 22 first moves forwardly to be in position to receive a fresh shuttle from the magazine and thereafter moves rearwardly to convey the shuttle to the lay.

The ejected shuttle falls down apron 27 toward the catcher box 28, and is held from dropping to the bottom of the box by plate 29. The latter is fixed to a shaft 30 pivoted on the box. A weighted lever 31 carrying a hook 32 is also fixed to 85 shaft 30 and is positioned so that as the conveyor 22 is moved forwardly at the beginning of replenishment the hook will enter a notch 20 in said lever. By the weighting of shaft 30 the hook will tend to enter the notch and if permitted to 90 do so will restrain the lever 22 from conveying a fresh shuttle to the lay. The presence of an ejected shuttle on the plate 29, as in Fig. 4, will overbalance the weighted effect and tend to rock the hook 32 away from notch 20. Lever 31 is prevented from rocking far enough to allow the shuttle to pass by plate 29, by engagement of a part of lever 22 when the latter is in normal forward position prior to its rearward movement incident to transfer. When the conveyor moves 95 100 rearwardly it releases lever 31 and the shuttle falls to the bottom of the box as indicated in Fig. 5.

A cam 33 on shaft 6 energizes a lever 34 fulcrumed at 35 and held against the cam by spring 105 36 between the frame and lever. As the cam 33 turns it presents at the proper time a raised portion 37 to lever 34, causing the top of said lever to be moved rearwardly and start the loom at the conclusion of the replenishment period, as 110

described in United States Patent No. 1,100,866 previously mentioned. A collar not used or shown herein is usually located on rod 42 in position to engage lever 34 and move the shipper mechanism to running position, whether or not transfer be normal.

In order to accomplish the purpose of the invention and prevent the loom being started if a shuttle is not ejected from the lay, a collar 41 is fixed to the starting connector 42 and carries a forward extending arm 43 pivoted at 44. The arm 43 is normally held in raised position, as in Fig. 1, by a projection 45 on a forwardly extending arm 46 of a bell crank lever pivoted at 47 to a stand 15 48 fixed to the frame. The lower arm 49 of the bell crank carries one end of a connector 50, the other end of which is carried by an arm 40 fixed to shaft 30. The latch or link 43 is therefore seen to be normally raised above the upper end of lever 34.

In operation, the shuttle will be ejected from the lay during the first part of the replenishing period and will slide down along apron 27 toward the catcher box 28. The conveyor lever 22, being at this time in relatively forward position with respect to the lever 31, will prevent the latter from rocking under the weight of the shuttle on plate 29. When the ejected shuttle reaches the plate 29, therefore, no further movement into the box will be permitted until after the conveyor lever has moved rearwardly.

As replenishment proceeds the lever 22 will move rearwardly out of restraining position with respect to lever 31 and the latter will be free to rotate in a clock-wise direction as viewed in Fig. 1 due to the weight of the shuttle resting on plate 29. The resultant rocking of lever 31 will move rod 50 rearwardly, and rock a bell crank lever 49 in a counter clock-wise direction about a fixed pivotal support 47. An arm 40 is secured to the shaft 30 and pivoted to the rod 50 and gives the latter its rearward impulse. Arm 46 and projection 45 are lowered and permit the link 43 to fall by gravity until it rests on the rod 42.

When link 43 is in the position just described an intermediate rise 51 on cam 33 will give the lever 34 a slight rearward movement to carry a locking lug 52 over a forward projection 53 on the link 43, thereby preventing upward movement of the link 43 under the action of the counter-weighted lever 31 when the shuttle moves off the plate 29 and into the catcher box. The counter-weighted lever maintains the lugs 52 and 53 in this position until the high point 37 of cam 33 causes lever 34 to move rearwardly, at which time the lug 52 will press against the latch 43 and move the same together with the rod 42 rearwardly.

The front end of rod 42 is connected to the shipper shaft 38 by means of an arm 39 so that rearward movement of the rod is accompanied by a restarting of the loom due to a shift in the shipper mechanism. A rear bearing 55 may be provided for the rod 42 if desirable.

If, for any reason, the depleted shuttle is not properly ejected, it will fail to reach the plate 29 and will not rock lever 31. The counter-weighted lever 31 will therefore hold the latch 43 raised so that rearward movement of lever 34 at the conclusion of the replenishing period will cause no movement of the shipper mechanism and the loom will remain at rest without resuming operation. The change shaft will complete its cycle, however, and then come to rest independently of the action of the shipper.

It is therefore seen that the ejected shuttle must reach a given or predetermined position in its path toward the catcher box before the loom can restart at the conclusion of the replenishing period. It will also be seen that the hook 32 acts to prevent conveyor lever 22 from having a transferring operation if the shuttle is not properly ejected, so that the rocking lever 31 performs the dual function of holding the conveyor lever and the latch 43 both inoperative should any defect arise in the ejection of the depleted shuttle. In other words, those parts of the replenishing mechanism which act to eject the depleted shuttle are free to perform their functions, but the movement of a fresh shuttle toward the lay and resumption of weaving are both prevented if the ejecting mechanisms fail to operate correctly or if the depleted shuttle behaves abnormally.

Having thus described my invention it will be seen that changes and modifications may be made therein by those skilled in the art without departing from the spirit and scope of the invention and I do not wish to be limited to the details herein disclosed, but what I claim is:

1. In a shuttle changing loom having a lay which stops to replace a depleted shuttle with a filled shuttle, means to eject a depleted shuttle from the lay when the latter is at rest, loom control means capable either of causing the loom to resume running or effective to prevent resumption of loom operation after replenishment, and means dependent upon presence of the ejected shuttle at a given point to cause the control means to effect resumption of loom operation. 105

2. In a shuttle changing loom which stops running during the replenishing period, means to eject a depleted shuttle from the lay along a given path, a change shaft rotatable during the replenishment period and effective to eject a 115 depleted shuttle from the loom, loom starting mechanism, and means controlled by the ejected shuttle to connect the mechanism and change shaft if the shuttle is ejected from the loom to render said shaft effective to restart the loom. 120

3. In a shuttle changing loom which stops running during the replenishing period, means to eject a depleted shuttle from the lay along a given path, a change shaft operative during the replenishing period to effect ejection of a 125 depleted shuttle and operative substantially at the end of the period to effect restarting of the loom, and means under control of the ejected shuttle to render the shaft effective to restart the loom after the ejected shuttle has reached 130 a given point in moving away from the lay of the loom.

4. In a shuttle changing loom which stops running during the replenishing period, means to eject a depleted shuttle from the lay along a given path, a shuttle box to receive the depleted shuttle, a change shaft operative during the replenishment period and effective to eject the depleted shuttle from the shuttle box, said change shaft capable of resuming loom operation at the 135 conclusion of the period, and means operated by the shuttle to render said shaft effective to restart the loom only upon the condition that the ejected shuttle reaches a given point in its movement away from the shuttle box. 140

5. In a shuttle changing loom which stops running during the replenishing period, means to eject a depleted shuttle from the lay along a given path, a member having a working stroke at the conclusion of the replenishing period, shipper 145

- mechanism, and means controlled by the ejected shuttle to connect the member and shipper mechanism and effective to restart the loom only upon the condition that the ejected shuttle reaches a given point in its movement away from the lay. 5
6. In a shuttle changing loom which stops running during the replenishing period, means to eject a depleted shuttle from the lay along a given path, loom starting mechanism, a member 10 normally operative at the conclusion of the replenishing period, and a force transmitting element controlling by the ejected shuttle to be interposed between and operatively connect the member and the starting mechanism to cause 15 resumption of loom running only upon the condition that the depleted shuttle is ejected. 15
7. In a shuttle changing loom which stops running during the replenishing period, means to eject a depleted shuttle from the lay along a given path, a member having a normal working 20 stroke at the conclusion of the replenishing period, a latch normally out of the path of the member and positioned operatively with respect to the member by the ejected shuttle, and shipper mechanism to start the loom dependent for 25 operation upon the cooperation of the member and the latch to resume loom operation at the conclusion of the period. 25
8. In a shuttle changing loom which stops running during the replenishing period, means to eject a depleted shuttle from the lay along a given path at the beginning of the replenishment period, means to restart the loom at the conclusion 30 of the replenishing period, and a controller for said means operated by the ejected shuttle and retaining indication of shuttle ejection until 35
- the conclusion of the replenishing period and effective then to cause resumption of weaving. 40
9. In a shuttle changing loom which stops running during the replenishing period, means to eject a depleted shuttle from the lay along a given path, at the beginning of the period, co-operating mechanism effective to restart the loom at the conclusion of the period and a controller for said mechanism to take the indication at the start of the period if the ejected shuttle reaches a given point in said path and hold said indication until near the conclusion of the period and thereafter render said mechanism effective to restart the loom at the conclusion of said period. 45
10. In a shuttle changing loom which stops running during the replenishing period, means to eject a depleted shuttle from the lay along a given path, shipper mechanism, a member having a normal stroke capable of operative relation with the shipper mechanism, and means dependent upon arrival of the ejected shuttle at a given point to connect the member and the shipper mechanism. 50
11. In a shuttle changing loom which stops running during the replenishing period, means to eject a depleted shuttle from the lay along a given path, a change shaft movable during the period of replenishment through a given cycle independently of the ejected shuttle, said shaft 100 coming to rest at the conclusion of the period, restarting means to be actuated by the shaft, and a controller to be actuated by the ejected shuttle if the latter reaches a given point in its path to connect the shaft and restarting means at the 105 completion of the replenishing period. 110
